(57) **CLAIM**

The ornamental design for a stylet, as shown and described.

DESCRIPTION

FIG. 1 is a top, front, right perspective view of a stylet, showing my new design,

FIG. 2 is a bottom, front, left perspective view of the stylet shown in FIG. 1,

FIG. 3 is a bottom side view of the stylet of FIG. 1,

FIG. 4 is a left side view of the stylet of FIG. 1,

FIG. 5 is a top side view of the stylet of FIG. 1,

FIG. 6 is a right side view of the stylet of FIG. 1,

FIG. 7 is a front side view of the stylet of FIG. 1; and,

FIG. 8 is a rear side view of the stylet of FIG. 1.

The stylet is shown with a symbolic break in its length. The appearance of any portion of the article between the break lines forms no part of the claimed design.
